Patented June 8, 1965

201,332

COMBINED STORAGE AND DISPLAY STAND FOR GOLF BAGS

John B. Caldwell, Canton, Ohio, assignor to The A. G.
Stafford Company, Canton, Ohio, a corporation of Ohio

Filed Apr. 23, 1964, Ser. No. 79,667

Term of patent 14 years

(Cl. D80—9)

Fig. 4

Fig. 2

Fig. 3

FIGURE 1 is a perspective view of a combined storage and display stand for golf bags showing my new design;

FIG. 2 is a front elevational view thereof;

FIG. 3 is a side elevational view thereof;

FIG. 4 is a top plan view thereof; and

FIG. 5 is a bottom plan view thereof.

The broken line illustration of golf bags and clubs shown in FIG. 3 are for illustrative purposes only.

I claim:

The ornamental design for a combined storage and display stand for golf bags, substantially as shown and described.
